UNITED STATES PATENT OFFICE.

LARS PETER SEAHOLM AND JOHN WILTON, OF DE KALB, ILLINOIS, ASSIGNORS TO THE AMERICAN STEEL & WIRE COMPANY OF NEW JERSEY, OF HOBOKEN, NEW JERSEY, A CORPORATION OF NEW JERSEY.

WIRE-WIPE.

1,224,967.

Specification of Letters Patent.

Patented May 8, 1917.

Application filed August 14, 1916. Serial No. 114,769.

To all whom it may concern:

Be it known that we, LARS PETER SEAHOLM and JOHN WILTON, citizens of the United States, and residents of De Kalb, in the county of Dekalb and State of Illinois, have invented certain new and useful Improvements in Wire-Wipers, of which the following is a specification.

Our invention relates to wire manufacturing devices and has particular reference to a novel wire wiping appliance adapted for use in connection with the galvanizing operation.

In the production of galvanized or coated wire it is common to pass the wire through a bath of molten metal and as a certain quantity of the molten material will adhere to the surface of the wire, it must be wiped to remove such surplus material. This wiping is commonly effected by employing upper and lower wads of fiber asbestos, the upper of which is replaceable frequently as required. The occasion for replacing this wipe is when a splice in the wire passes through the wire wiping appliance. Inasmuch as the upper wipe is removed by the splice, it becomes necessary to supply another at once. This is quickly attended to by the operator, the result being accomplished by lifting the means used to press the wad down on the wire, placing a new wad in place and returning the holding means to proper location. A difficulty has arisen in this structure which may be described as follows: If a wad or wipe is laid loosely on the wire as the wire is passing thereunder, the face of the wad will take up and retain a quantity of the semi-molten material, which material will adhere to the wipe and make a rough wiping surface which results in an uneven wipe. This difficulty is avoided if the first contact of the wipe with the wire is coincident with a sufficient pressure to cause the molten material to be taken up by the outer edge of the wipe.

An object, therefore, of the present invention is to provide a device which shall upon the removal of the old wad and the retraction of the plunger or holding device, substitute a new wipe, which wipe shall be supported above the wire and out of contact therewith until the plunger is forced downward, the plunger forcing the said wad di-

rectly against the wire and preventing the accumulation of metal underneath the wipe.

The invention will be more readily understood by reference to the accompanying drawings, wherein—

Figure 1 is a vertical section through a wire wiping appliance such as contemplated by us and showing the parts in their normal operative condition;

Fig. 2 is a similar view showing the parts in the position they will assume just prior to the furnishing of a new wad for the upper wipe, and

Fig. 3 is an enlarged elevation of the form of the upper wad employed by us.

In the drawings, it will be seen that the wire 10 has passed through a galvanizing tank 11 containing a quantity of spelter or other coating material. The splice 12 in the wire is about to contact the wire wipes and remove the upper wipe. The bottom wipe 13 is held in a suitable recess in the support 14, the upper wipe 15 merely resting upon the wire and being held firmly thereagainst by the plunger 16, which is guided in apertures in the frames 17, the extent of pressure exerted by the plunger being regulated by the arm 18, which may be weighted if desired. It will be understood that a plurality of these wiping appliances are placed in juxtaposition, inasmuch as a plurality of wires pass through the same tank.

The plunger 16 is located in an inclined position; that is, in a position perpendicular to the wire as it passes out of the tank. Leaning against the plunger and supported on the ledge 19 adjacent to the plunger is the wad or wipe 20, this wad being ready to fall into the opening provided by the retraction of the plunger 16 into the position of Fig. 2. It will be seen, however, that because of the flanged upper end of the wad, which flange is of greater diameter than the diameter of the plunger and of the opening through which the same operates that the wad is retained in the opening in the position shown in Fig. 2; that is, above and out of contact with the wire. As the plunger is returned to the position of Fig. 1, the wad is forced down upon the wire, the action being so quick as to prevent the accumulation of any metal underneath the wad.

Of course, the exact shape of the wad or

wipe and the mechanism by which the same is controlled are immaterial, the idea being to provide a wad and suitable mechanism whereby the wad shall be retained just above the wire until the holding plunger ejects the same from the wad-holding means and forces the same at once against the wires. It will be seen, therefore, that modifications of the apparatus such as 10 would secure the results referred to would be within the spirit of our invention.

We claim:

- 15 1. In a wire wiping appliance, the combination of a lower wipe, a removable upper wipe, a plunger for holding the last named wipe against a wire, a fixed ledge having an aperture through which said plunger is adapted to pass, a replacing wipe being so shaped as to be retained in said aperture during the retraction of said plunger, whereby upon the return of said plunger said wipe is immediately forced into firm engagement with said wire, substantially as described.
- 20 2. In a wire wiping appliance, the combination of a support for a lower wipe, an upper wipe, a plunger for forcing the latter into engagement with a wire, a lever for

actuating said plunger, a frame member having an opening for the accommodation 30 of said plunger, a replacing upper wipe having a flange of a diameter greater than the size of said opening, whereby the same is retained in the opening upon the retraction of said plunger until forced out of the 35 opening by said plunger and directly into engagement with said wire, substantially as described.

3. In a wire wiping appliance, the combination of a support, a plunger and a wire 40 wiping wad having a flange on one end thereof, and means adapted to accommodate said wad and retain the same above a wire by reason of engagement with the flange of said wad, whereby said plunger may act 45 upon said wad to force the same instantly into engagement with the wire, substantially as described.

Signed at De Kalb, Illinois, this 2nd day of August, 1916.

LARS PETER SEAHOLM.
JOHN WILTON.
